REINFORCING FITTING FOR DECK
OPENINGSHarry B. Maris and John A. Sanderson,
Washington, D. C.

Application December 3, 1942, Serial No. 467,738

7 Claims. (Cl. 189—34)

(Granted under the act of March 3, 1883, as
amended April 30, 1928; 370 O. G. 757)

This invention relates to a reinforcing fitting for use around hatch and other openings in decks or similar structures.

It is well known that high concentrations of stress occur in the deck plates of ships around the corners of openings of a rectangular or similar shape when the deck is placed under tension. The application of such stresses to the decks of ships is a matter of common occurrence, since it takes place each time the ship is supported by a wave or swell beneath its mid-section while its ends are lying in the troughs of such waves. For this reason, such openings, though necessary, constitute a serious impairment of the strength and seaworthiness of the vessel.

In the past it has been common practice to double the thickness of the deck plating around the edges of such openings in an effort to overcome the above mentioned weakening effect. While this practice usually succeeded in protecting the plating around the edge of the opening, in doing so it often introduced high concentrations of stress in the plating at other points.

It is an object of this invention to provide a reinforcing means for use around rectangular and other openings in decks or similar structures which, when the deck is under tension, will prevent the formation of high concentrations of stress due to the presence of the opening.

It is a further object of the invention to provide reinforcing means around such openings to take the load which would have been borne by the omitted plating, said reinforcing means being of such construction and form that its behavior with respect to the surrounding plate, while undergoing such stress, will be substantially that of the omitted plate.

Other objects will become apparent from a careful consideration of the following description when taken together with the accompanying drawing in which:

Fig. 1 is a plan view of a segment of deck plating having a rectangular opening formed therein and a reinforcing means embodying the invention applied thereto;

Fig. 2 is a cross-sectional view taken along the line 2—2 of Fig. 1, and

Fig. 3 is a plan view of a second embodiment of the invention.

In Fig. 1 there is represented by reference character 10 a section of a deck of a ship, the stress in the deck being a uniform tension along the Y axis as shown by the arrows. The deck

has formed in it a rectangular opening 11 such as might constitute a part of a hatch.

In accordance with the invention, accumulations of stress are prevented by the use of a reinforcing fitting employing the principles of the suspension bridge. Such a fitting is indicated generally in Fig. 1 by the reference numeral 12. It is made up of a plurality of connected members, two of which marked AB and CD, extend parallel to opposite sides of opening 11 and likewise parallel to the direction of the lines of stress. Connecting points B and D and points A and C are members BND and AOC respectively, both formed in the shape of substantially parabolic arches.

These arches receive the load from the deck plating and transmit it to the longitudinal members AB and CD. Transverse members AC and BD are provided at the bases of the arches to withstand compressional stresses along the X axis and thus serve to maintain equilibrium between the forces in AOC and BND and the forces in AB and CD.

It will be seen that the arches of the fitting act in the same capacity as the cables of a suspension bridge, the road bed of which is of uniform weight per unit length. The uniform tension existing in the plating and represented by the arrows in Fig. 1 corresponds to the weight of the road bed of the suspension bridge.

It will be noted that in Figure 2 the fitting is shown as made of I-beams. This, however, is only by way of example, as the fitting may equally well be made up of sheet stock. If important bending stresses in the beam resulting from the non-symmetrical load applied only to one side are to be avoided, the height of the stock or beam section above the plating should be less than $\frac{1}{15}$ th of the overall length of the fitting. The fitting may be cast as a whole or may be fabricated, various parts being joined by any convenient means such as welding or riveting. The fitting is shown at 13 in this figure as being joined to the deck plating by welding. Any other convenient means of securing it to the deck may be followed. However, regardless of what method is employed, the points of connection between the fitting and the deck plating should be numerous and equally spaced. Although the fitting is shown in Figures 1 and 2 as being applied to the upper surface of the deck plating, it may be applied to the lower surface if desired.

The cross-sectional area of each fitting member should be equal to the product of the half-

width of the opening and the thickness of the deck plate, except that the members AC and BD should be so designed that their compressional strength is equal to the product of the stress of the longitudinal member AB or CD and co-tangent θ where θ is the angle between the tangent to the curve at point P in Figure 1 and the X axis. The value of θ depends upon the allowable dimensions and weight of the fitting. It has been found that tangent $\theta=2.5$ represents a practical value resulting in a fitting in the form of Figure 1.

With the type of fitting illustrated in Figure 1, concentrations of stress in the plate are only 6% greater than the applied tensile strength, whereas if no fitting is used, concentrations of stress as much as 100% greater than the applied tensile strength may be expected.

The efficiency of any fitting of different shape will be less than that of the parabolic form here described but will be efficient in proportion to its approximation to the parabolic form. In Fig. 3 is shown a fitting similar to that of Fig. 1 but having its arches composed of chord-like members which approximate the parabolic curve. Thus points B and D are joined by chords BS, ST and TD and the points A and C are joined by chords AQ, QR and RC. Such a fitting has been found to closely approach the behavior of the ideal type shown in Fig. 1.

While the use of the fittings embodying the invention has been shown only as applied to rectangular deck openings, they may likewise be applied to openings of other shapes. If the opening does not have sides parallel to the direction of application of stress, then the cross-sectional area of the members should be calculated by substituting half the maximum dimension transverse to longitudinal members AB and CD for the half-width of the opening.

The invention described herein may be manufactured and used by or for the Government of the United States of America for governmental purposes without the payment of any royalties thereon or therefor.

We claim:

1. Means for reenforcing the edges of an opening in a plate which is under uniform unidirectional tension, comprising a fitting secured to said plate around said opening, said fitting comprising a pair of longitudinal members extending along opposite sides of said opening and parallel to the direction of application of said tension, a pair of members extending transversely between said longitudinal members, and a pair of members each having substantially the form of a parabola and each joining a pair of corresponding ends of said longitudinal members, all of said members being rigidly secured together into a unitary structure.

2. Means for reenforcing the edges of an opening in a plate which is under uniform unidirectional tension, comprising a fitting secured to said plate around said opening, said fitting comprising a pair of longitudinal members extending along opposite sides of said opening and parallel to the direction of application of said tension, a pair of members, each having substantially the shape of a parabola and each joining a pair of corresponding ends of said longitudinal members, and a transverse member extending between the ends of each of said parabolic members, all of said members being rigidly secured together into a unitary structure.

3. Means for reenforcing the edges of an opening in a plate which is under uniform unidirectional tension, comprising a fitting secured to said plate around said opening, said fitting comprising a pair of longitudinal members extending along opposite sides of said opening and parallel to the direction of application of said tension, a pair of members, each having substantially the shape of a parabola and each joining a pair of corresponding ends of said longitudinal members, and a transverse member extending between the ends of each of said parabolic members, all of said members being rigidly secured together into a unitary structure, the cross-sectional area of said longitudinal and parabolic members being equal to the product of half the maximum dimension of said opening in a direction transverse to said longitudinal members and the thickness of said plate.

4. Means for reenforcing the edges of an opening in a plate which is under uniform unidirectional tension, comprising a fitting secured to said plate around said opening, said fitting comprising a pair of longitudinal members extending along opposite sides of said opening and parallel to the direction of application of said tension, a pair of members, each having substantially the shape of a parabola and each joining a pair of corresponding ends of said longitudinal members, and a transverse member extending between the ends of each of said parabolic members, all of said members being rigidly secured together into a unitary structure, the cross-sectional area of said longitudinal and parabolic members being equal to the product of half the maximum dimension of said opening in a direction transverse to said longitudinal members and the thickness of said plate, and the compressional strength of each of said transverse members being equal to the product of the maximum expected stress on one of said longitudinal members and the co-tangent of the angle between a line tangent to one of said parabolic members at its point of origin and a line normal to the direction of application of said stress.

5. Means for reenforcing the edges of an opening in a plate which is under uniform unidirectional tension, comprising a fitting secured to said plate around said opening, said fitting comprising a pair of longitudinal members extending along opposite sides of said opening and parallel to the direction of application of said tension, a pair of members, each composed of at least three segments symmetrically proportioned and forming chords of a parabola, each of said members joining a pair of corresponding ends of said longitudinal members, and a transverse member extending between the ends of said longitudinal members, all of said members being rigidly secured together into a unitary structure.

6. Means for reenforcing the edges of an opening in a plate which is under uniform unidirectional tension, comprising a fitting secured to said plate around said opening, said fitting comprising a pair of longitudinal members extending along opposite sides of said opening and parallel to the direction of application of said tension, a pair of members, each composed of at least three segments symmetrically proportioned and forming chords of a parabola, each of said members joining a pair of corresponding ends of said longitudinal members, and a transverse member extending between the ends of said longitudinal members, all of said members being rigidly secured together into a unitary structure, the cross-

sectional area of said longitudinal and segmented members being equal to the product of half the maximum dimension of said opening in a direction transverse to said longitudinal members and the thickness of said plate.

7. Means for reenforcing the edges of an opening in a plate which is under uniform unidirectional tension, comprising a fitting secured to said plate around said opening, said fitting comprising a pair of longitudinal members extending along opposite sides of said opening and parallel

to the direction of application of said tension, a pair of members, each composed of a plurality of segments symmetrically proportioned and forming chords of a parabola, each of said members joining a pair of corresponding ends of said longitudinal members, and a transverse member extending between the ends of said longitudinal members, all of said members being rigidly secured together into a unitary structure.
